US00D767515S

(12) **United States Design Patent** (10) **Patent No.:** **US D767,515 S**
Eguchi et al. (45) **Date of Patent:** **** Sep. 27, 2016**

(54) **LIGHT EMITTING DIODE**

(71) Applicants: **CITIZEN ELECTRONICS CO., LTD.**, Yamanashi (JP); **CITIZEN HOLDINGS CO., LTD.**, Tokyo (JP)

(72) Inventors: **Hiroaki Eguchi**, Yamanashi (JP); **Toshiaki Ishihara**, Yamanashi (JP)

(73) Assignees: **Citizen Electronics Co., Ltd.**, Yamanashi (JP); **Citizen Holdings Co., Ltd.**, Tokyo (JP)

(**) Term: **14 Years**

(21) Appl. No.: **29/523,139**

(22) Filed: **Apr. 7, 2015**

(30) **Foreign Application Priority Data**

(57) **CLAIM**

The ornamental design for a light emitting diode, as shown and described.

DESCRIPTION

FIG. 1 is a perspective view of a light emitting diode showing our new design;

FIG. 2 is a top plan view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a bottom plan view thereof.

The broken lines shown in the drawings are for illustrative purposes only and form no part of the claimed design.

1 Claim, 5 Drawing Sheets
